(57) **CLAIM**

The design for a shoe cover with cleats, as shown and described.

DESCRIPTION

FIG. 1 is a perspective view of a shoe cover with cleats in accordance with my design;

FIG. 2 is a bottom plan view thereof;

FIG. 3 is a left side elevational view thereof;

FIG. 4 is a right side elevational view thereof;

FIG. 5 is a front elevational view thereof;

FIG. 6 is a rear elevational view thereof; and,

FIG. 7 is a side elevational view in an alternate position of the shoe cover.

The broken lines shown are included for the purpose of illustrating the unclaimed portions of the shoe cover with cleats and form no part of the claim.

1 Claim, 6 Drawing Sheets

FIG. 2

FIG. 3

FIG. 4

FIG. 5

FIG. 6

FIG. 7
